Primary Examiner — Calvin E Vansant*Assistant Examiner* — Giang Hoang Tran(74) *Attorney, Agent, or Firm* — Faegre Drinker Biddle & Reath LLP(57) **CLAIM**

We claim the ornamental designs for a side panel of a utility vehicle, as shown and described.

DESCRIPTION

FIG. 1 is a left front perspective view of a side panel of the utility vehicle showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the side panel of the utility vehicle shown in broken lines form no part of the claimed design.
